UNITED STATES PATENT OFFICE.

ERNEST SPENCER BOWEN, OF AUBURN, NEW YORK.

GOVERNOR FOR STEAM-ENGINES.

SPECIFICATION forming part of Letters Patent No. 447,039, dated February 24, 1891.

Application filed June 14, 1890. Serial No. 355,443. (No model.)

To all whom it may concern:

Be it known that I, ERNEST SPENCER BOWEN, a citizen of the United States, residing at Auburn, in the county of Cayuga and State of New York, have invented certain new and useful Improvements in Automatic Governors for Steam-Engines; and I do hereby declare the following to be a full, clear, and exact description of the invention, such as will enable others skilled in the art to which it appertains to make and use the same.

My invention is an improvement in automatic governors for steam-engines; and it consists in the novel features of construction hereinafter fully described.

I have illustrated my invention in the accompanying drawings, and the same is fully disclosed in the following description and claims.

Referring to the said drawings, Figure 1 is a side view of my improved valve-gear applied to the driving-wheel of the engine-shaft. Fig. 2 is an end view of the same with the shaft broken away and the wheel removed.

Fig. 3 is a view of a slightly-modified construction. Fig. 4 is a view showing a modified construction for adjusting the springs. Fig. 5 is a detail of part of the mechanism.

My invention relates particularly to the type of governors in which the eccentric is caused to shift its position and change its degree of eccentricity, thereby shortening or lengthening the stroke of the valve-rod and admitting less or more steam to the piston, thus correcting the variations in the speed of the engine which would otherwise be caused by the change of load, pressure, or other causes.

The object of my invention is to provide an automatic governor of very simple construction and an improved means for adjusting the resistance-springs of the same, so as to secure the desired speed of the engine-shaft.

In the said drawings, A represents the driving-wheel mounted on the engine-shaft B. The sliding eccentric hub C is secured to a frame D, and said hub is provided with a slot c, which engages the engine-shaft B. The frame D may be cast integrally with the hub C or suitably secured thereto, and is provided with two arms d d, extending outwardly on

each side of the shaft B. The outer extremities of these arms are connected to the wheel A by means of the spring E, by means of which the eccentric hub is caused to revolve with the wheel and actuate the eccentric-strap F, which is connected to the slide-valve of the steam-chest in the usual manner. These springs E are rigidly secured to the ends of arms d in any desired manner, and they are also secured to the wheel A at or adjacent to the periphery of the same, preferably by means of an improved clip G, which enables me to secure any desired adjustment of the springs to vary the tension thereof. This clip G is best seen in Fig. 5, and consists of a block having one side corresponding to an arc of a circle considerably smaller than the wheel A. This block is provided with a central recess or slot g, which receives the end of the spring. The block G is secured, preferably, to any inner face of the rim of the wheel A by means of two bolts g' g', which may be tapped into the wheel or extend from the outside of the same through the rim and block G and be provided with nuts, as found most convenient or desirable. The curved face of the block G conforming to the circumference of a smaller circle than the rim of the wheel A, the said block will touch said rim at one point only, and by adjusting the said block by means of the bolts g' g' the said block can be made to assume different positions as the one end or the other is brought nearer to the rim of the wheel. In order to facilitate this action, I prefer to employ a rocker H, which consists of a bolt or rod engaging a notch in the rim of the wheel A or the block G, or both, by means of which the adjustment can be more readily accomplished, the block G turning upon the rocker H as on a pivot.

The springs E are placed in engagement with the recesses g of the respective adjusting-blocks G and are securely attached to the arms d d of the frame D, as before stated. In order to secure the springs E rigidly in the recesses g, I prefer to employ one or more wedges e, of spring material, which are driven into said recesses by the side of said springs and force the latter rigidly against the wall of said recesses. These wedges are preferably made of spring material, so as not to inter-

fere with the action of said springs, and they may be made of sufficient length to serve to re-enforce said springs, as shown in the drawings.

5 The springs E could be secured in the blocks G by means of suitable clamps, if desired; but this is my preferred construction, as it is very simple. The wedges e can be made of sufficient length to re-enforce the 10 springs E, if desired.

The springs E secure the frame D and eccentric hub C to rotate with the wheel A and hold said hub with one end of its slot c against the shaft B, so as to give the hub its greatest 15 amount of eccentricity and cause the slide-valve rod and valve to move the full extent of its stroke.

To the frame D is secured a weighted arm K, carrying the weight L, secured thereto in 20 any desired manner and extending radially from the center of the wheel. This weighted arm may form a continuation of one of the arms d, as shown in Fig. 1, or it may extend 25 separately from the frame, as shown in Fig. 2; but the arrangement must be such that the longest diameter of slot c and the said weighted arm shall extend substantially perpendicularly to the springs E or in substantially the line of tension of said springs.

30 In Fig. 1 the arms d extend from the frame D at right angles to the springs E; but this is not essential, as they may extend at an angle, as shown in Fig. 3, in which case the springs E will be longer or shorter, according 35 to the angle which the arms make with the said springs.

The operation of the device will be apparent from the drawings, in connection with the foregoing description. When the wheel A is 40 revolved, it moves slowly at first, and the eccentric gives the valve the full stroke, throwing the parts open to their fullest extent. As the wheel attains a considerable velocity, the weight L, attached to the eccentric-carrying 45 frame, will be moved toward the periphery of the wheel A by centrifugal force, and thereby move the said frame and the eccentric hub in the direction indicated by the arrow against the tension of the springs. The movement 50 of the eccentric hub is permitted by the slot c, before described, and the eccentricity of the hub is thus diminished, shortening the travel of the valve and decreasing the amount which the ports are opened. It will thus be seen 55 that by this construction any variations of pressure, load, or from other causes will be compensated for and equalized, for if there is a decrease of pressure there will be a tendency of the wheel to slow up; but the weight 60 will instantly respond and be drawn in by the springs toward the center, and thereby increase the eccentricity of the hub C and the travel of the valve and admit more steam to the cylinder of the engine. In case the pressure 65 is increased or the load removed, so that the wheel has a tendency to revolve more rapidly, the weight flies out nearer the periphery

of the wheel and decreases the eccentricity of the hub C and the travel of the valve. This construction forms an exceedingly sensitive 70 automatic governor, which will respond instantly to the slightest variations, however caused, thereby producing a smooth and uniform speed of the engine-shaft.

In order to vary the mean or uniform speed 75 at which it is desired to run the engine-shaft, it is only necessary to vary the tension of the resistance-springs, as will be readily understood. If it is desired to run at a higher speed, the resistance should be increased, and 80 vice versa. This adjustment is accomplished by means of the rocking adjusting-blocks hereinbefore described and the bolts which 85 secure them to the rim of the wheel. The walls of the recesses engaged by the spring being straight, it will be seen that moving the said blocks on their rockers in one direction or the other will adjust the tension of the 90 springs, and this can be easily and quickly effected.

In Fig. 4 I have shown a slightly-modified construction for adjusting the tension of the springs E. In this instance I employ longer 95 springs having portions extending at right angles to the part which engages the frame D. These springs are supported at their central 100 points in suitable sockets G', attached to the rim of the wheel, and may be secured therein in any suitable way, as by pins. (Shown in dotted lines.) The outer ends of said springs 105 are then secured to the rim of the wheel by means of a bolt h and nut, and the springs E are adjusted by this means, as will be readily 110 understood.

What I claim, and desire to secure by Letters Patent, is—

1. In an automatic governor for steam-engines, the combination, with the driving-shaft and the wheel mounted thereon, of a movable eccentric for actuating a slide-valve, the 110 weight connected thereto, and springs forming the sole connection between said eccentric and wheel, said eccentric being adapted to move bodily in a direction in line with the tension of said springs, substantially as described. 115

2. In an automatic governor for steam-engines, the combination, with the driving-shaft and the wheel mounted thereon and adapted to turn therewith, of a movable eccentric for 120 actuating a slide-valve, having a slot engaging said shaft, a weight secured to said eccentric, and springs forming the sole connection between said eccentric and the wheel, said slot being arranged in line with the tension 125 of said springs, substantially as described.

3. In an automatic governor for steam-engines, the combination, with the driving-shaft and wheel, of a movable eccentric provided with a slot engaging said shaft, a weighted 130 arm secured to said eccentric, and springs forming the sole connection between the eccentric and wheel and extending at right angles to said weighted arm, said slot extending

- in line with said weighted arm, substantially as described.
4. In an automatic governor for steam-engines, the combination, with the driving-wheel, 5 the movable eccentric hub for actuating the slide-valve, provided with a weight, springs connected rigidly with said hub, the adjustable blocks rigidly engaging said springs, and means for securing said blocks adjustably to 10 said wheel, substantially as described.
5. In an automatic governor for steam-engines, the combination, with the driving-wheel, 15 of the movable eccentric hub for actuating the slide-valve, provided with a weight, springs rigidly connected to said hub, the adjustable rocking blocks having recesses to receive the ends of said springs, the wedges for securing said springs in said blocks, and means for 20 adjustably securing the said blocks to the rim of the wheel, substantially as described.
6. In an automatic governor for steam-engines, the combination, with the driving-wheel, of the movable eccentric for actuating the
- slide-valve, provided with a weight, the springs rigidly connected to the said hub, the adjustable blocks having recesses to receive said springs, and the spring-wedges for securing said springs in said recesses and re-enforcing said springs, substantially as described. 25
7. In an automatic governor for steam-engines, the combination, with the driving-wheel, of the movable eccentric for actuating the slide-valve, the weight attached thereto, the springs rigidly connected to said eccentric, the adjustable blocks for engaging said springs, 30 means for securing said blocks adjustably to the rim of the wheel, and the rocker interposed between the block and wheel, substantially as described. 35

In testimony whereof I affix my signature in 40 presence of two witnesses.

ERNEST SPENCER BOWEN.
